US00D703314S

(12) **United States Design Patent**
Schneider et al.

(10) **Patent No.:** **US D703,314 S**
(45) **Date of Patent:** **** Apr. 22, 2014**

(54) **SELF INJECTION DEVICE**

(75) Inventors: **Jared Schneider**, Cranston, RI (US);
Mark Joseph Guarraia, Cranston, RI (US); **Margaux Frances Boyaval**, Warwick, RI (US); **Ryan James Shafer**, Whitinsville, MA (US)

(73) Assignee: **Becton, Dickinson and Company**, Franklin Lake, NJ (US)

(**) Term: **14 Years**

(21) Appl. No.: **29/418,253**

(22) Filed: **Apr. 13, 2012**

(51) **LOC (10) Cl.** **24-02**

(52) **U.S. Cl.**

USPC **D24/113**

(57) **CLAIM**

The ornamental design for a self injection device, as shown and described.

DESCRIPTION

FIG. 1 is a perspective view of an embodiment of a self injection device showing our new design, with a cap shown in a secured position;

FIG. 2 is a front elevational view of the self injection device shown in FIG. 1;

FIG. 3 is a top view of the self injection device shown in FIG. 1;

FIG. 4 is a left side elevational view of the self injection device shown in FIG. 1;

FIG. 5 is a right side elevational view of the self injection device shown in FIG. 1;

FIG. 6 is a bottom view of the self injection device shown in FIG. 1; and,

FIG. 7 is a rear elevational view of the self injection device shown in FIG. 1.

1 Claim, 4 Drawing Sheets
